DESIGN FOR A SMOKER'S PIPE

Rube L. Miller, Seattle, Wash.

Application February 5, 1940, Serial No. 90,041

Term of patent 7 years

To all whom it may concern:

Be it known that I, Rube L. Miller, a citizen of the United States, residing at Seattle, in the county of King, State of Washington, have invented a new, original, and ornamental Design for Smoker's Pipe, of which the following is a specification, reference being had to the accompanying drawing, forming part thereof.

I claim:

The ornamental design for a smoker's pipe, as shown.

RUBE L. MILLER.
